Atto.

UNITED STATES PATENT OFFICE.

FREDERIC H. BENDER, OF CHICAGO, ILLINOIS, ASSIGNOR TO AMERICAN STEEL FOUNDRIES, OF CHICAGO, ILLINOIS, A CORPORATION OF NEW JERSEY.

BRAKE-HANGER MECHANISM.

Application filed April 12, 1923. Serial No. 631,514.

To all whom it may concern:

Be it known that I, FREDERIC H. BENDER, a citizen of the United States, residing at Chicago, in the county of Cook and State of Illinois, have invented certain new and useful Improvements in Brake-Hanger Mechanism, of which the following is a specification.

This invention relates to brake hanger mechanism.

In the application of brake hangers to their supports, among other things, it is essential to consider proper clearance to accommodate movements of the brakes when the brake shoe and wheels are new and when worn, and also to consider the safety with which the brake hanger is held by its support to prevent falling of the brake mechanism and possible wrecking of a train, and at the same time consider the rapidity with which parts may be assembled and disassembled.

One object of the invention is to provide simple, novel and efficient means for securely supporting brake hangers to meet the requirements above mentioned.

Another object is to provide a simple brake hanger arrangement in which the parts are interlocked in a manner which insures safety in addition to a rapid assembly and disassembly of the parts, and in general adapted to meet the various requirements for successful use under service conditions.

These and other objects are accomplished by means of the arrangement disclosed on the accompanying sheet of drawings, in which—

Figure 1 is a transverse sectional view through a side frame showing a brake hanger bracket and means for securing the brake hanger therein;

Figure 2 is a bottom plan view of the arrangement shown in Figure 1; and

Figure 3 is a sectional view taken in the plane of line 3—3 of Figure 1.

The various novel features of the invention will be apparent from the following description and drawings and will be particularly pointed out in the appended claims.

Referring to the figures of the drawings, it will be noted that the invention is illustrated in connection with a side frame 10 having an integrally formed bracket 11 having a transverse opening 12 which is partially closed at the underside by two lips 13

and 14 which extend toward each other and which act as a support for a bracket hanger key 15 which is slidably mounted within the bracket and rests upon the lips 13 and 14, said key being applied to the bracket and withdrawn therefrom by a longitudinal sliding movement.

This key is provided with a semi-cylindrical groove 16 in its upper surface for the reception of the upper horizontal portion 17 of a brake hanger having downwardly extending arms 18 which are located on either side of the key and which, when the brake hanger is in normal operative position, embrace opposite sides of the lip 13 to prevent lateral displacement of the hanger and also to prevent lateral displacement of the key 15 with respect to the bracket 11. In other words, while the key 15 locks the hanger against downward displacement, the hanger in cooperating with the bracket prevents displacement of the key. It will be appreciated, of course, that the hanger is swung inwardly into the position shown in dotted lines in Figure 3, when it and the key 15 are applied to or withdrawn from the bracket. The upper wall of the opening 12 also has a semi-cylindrical portion for receiving the upper half of the upper horizontal portion 17 of the brake hanger so that the latter is embraced both by the bracket portion and by the removable key.

As the greater part of the wear due to the weight of supported parts is downward, such wear comes on key 15, but this key can be replaced at relatively small expense. The other parts of the bracket or means for supporting the hanger are subject to little or no wear. Furthermore, with this arrangement it is impossible to forget to insert the locking element, for in this case the locking element is the key 15 which also supports the brake hanger.

It is my intention to cover all modifications of the invention falling within the spirit and scope of the following claims.

I claim:

1. In brake mechanism, the combination of a key supporting member having an undecurved lip, a key movably mounted on said member, and a brake hanger carried by said key, said brake hanger and lip having interengaging portions to prevent accidental displacement of said key.

2. In brake mechanism, the combination

of a key supporting member including an undercurved lip, a key supported by said lip, and a brake hanger carried by said key.

3. In brake mechanism, the combination 5 of a key supporting member including lips, a key supported by said lips, and a brake hanger carried by said key, one of said lips and hanger having interengaging portions for locking said key in a given position.

10 4. In brake mechanism, the combination of a key supporting member having lips extending toward each other, a key supported by said lips, and a brake hanger carried by said key, said brake hanger and key being 15 placed within said lips when the brake hanger is in a given position, one of said lips

and said hanger cooperating to prevent displacement of the latter and said key when the hanger is in a different position.

5. In brake mechanism, the combination 20 of a key supporting member, a key movably mounted in said member, and a brake hanger carried by said key, said key and hanger being applied to said key supporting member when said hanger is in a given position, said 25 member and hanger having interengaging parts for preventing accidental displacement of said key and hanger when the latter is in another position.

Signed at Chicago, Illinois, this 7th day 30 of April, 1923.

FREDERIC H. BENDER.
